UNITED STATES PATENT OFFICE.

FREDERICK B. KIRKNESS, OF NEWARK, DELAWARE.

BALL-SLINGER.

1,075,041.

Specification of Letters Patent.

Patented Oct. 7, 1913.

Application filed March 24, 1913. Serial No. 756,012.

To all whom it may concern:

Be it known that I, FREDERICK B. KIRKNESS, a subject of the King of England, residing at Newark, in the county of New Castle and State of Delaware, have invented certain new and useful Improvements in Ball-Slingers; and I do declare the following to be a full, clear, and exact description of the invention, such as will enable others skilled in the art to which it appertains to make and use the same.

This invention relates to games, and more especially it is a throwing device or slinger for aerial projectiles; and the object of the same is to produce an implement of this character by means of which a ball may be picked up from the ground in the mouth of the slinger and thrown a great distance by hand, without touching the ball at all. This and other objects are accomplished by constructing the slinger in the manner herein-after more fully described and claimed, and as shown in the drawings wherein—

Figure 1 is a side elevation of this implement complete, and Fig. 2 is a similar elevation at right angles thereto. Fig. 3 is a longitudinal section of a modification. Fig. 4 is an end elevation and Fig. 5 is a cross section on the line 5—5 of Fig. 1.

In the drawings the numeral 1 designates a handle, preferably of wood and preferably having a hand grip 2 of some shape or character at what might be called its inner end. I may say here that the entire device may be turned from a single piece of hard wood, and will approximate twenty-four inches in length, although these details and the finish of the slinger are matters of no moment. At what might be called its upper or outer end the handle is forked as shown at 3, the fork-arms being drawn together to a degree desired by means of a screw 4 or other device. Above or beyond this screw these arms are preferably weakened as by exterior cross grooves 5, and beyond these grooves in turn the arms are enlarged into jaws 6 dished or curved on their inner faces as at 7 to form a pocket 8 in the end of the implement.

In Fig. 2 is shown a slight modification, where the jaws 16 are formed of two curved metal members passing around the outer side of the fork-arms and secured thereto by screws 17 or otherwise, the extremity of the wooden handle being in this instance cut off

flat at a point 18 some distance above the weakening grooves 5.

In use the player grasps the slinger by taking hold of the hand grip 2 and carries it to the point of use. As it then hangs pendant from the hand, a ball B can be picked up by passing the mouth of the pocket over the ball—the pocket having been adjusted to the proper size by setting up the screw 4. Careful adjustment of this screw will adapt the pocket to whatever ball is being employed, but ordinarily I use golf balls of rubber or similar slightly clinging material. The same will slip into or out of the pocket with an amount of friction dependent upon the setting of the screw 4 which is an easy matter. Having picked up the ball, the player is at liberty to cast or throw it as he desires, but ordinarily he will retract his arm, stiffen the wrist, throw the hand outward and backward so that the outer end of the slinger is far remote from and to the rear of his body, and then sweep his arm over his shoulder and forward and bring the hand to a sudden stop when the implement has been carried to a point probably about level with his eye. The axis of the pocket at this time is on a line extending from his eye upward and forward in the direction the ball is to be cast, and the result of the momentum thus imparted to the ball and the circumferential force set up as the implement is swung over the shoulder will be that the ball will fly out of the pocket and may be cast or slung to a distance dependent on the strength of the player, his skill, the weight of the ball or missile, and the nicely to which the screw 4 has been adjusted.

It is quite possible that an implement of this character may be used for pitching balls in games of base ball, and in that case a considerable curve could be given to the ball if the player were sufficiently dexterous. It will be noticed that the crack or space 3 between the arms of the fork is of liberal width, and this might be amplified to such an extent that if the implement were swung by the arm in an arc which passed through this space, the projected ball would be given no curve or twist, whereas if the handle were turned on its axis for a quarter revolution so that both of the faces of the jaws were in the line of said arc, the ball as it left the pocket would be "curved" to a

degree dependent on the pitcher's dexterity. It is possible also that an implement of this character might be used in hunting or in warfare, for throwing missiles such as shot or small bombs; and this suggestion leads to the thought that it might be used as a general plaything for casting anything, as for instance throwing balls at a target or tossing the weight of a plumb line. It is only 5 essential to the successful operation of the device that the articles handled by it be of a uniform or substantially uniform size, or else that the jaws have considerable elasticity so as to grasp articles that vary in 10 size. However, it is my intention that this improved slinger shall form the hand implement of a game to be known by the title of "Slinger," wherein the implement in effect takes the place of the sticks used in 15 the game of golf, but details of the game need not be elaborated in this specification.

What is claimed as new is:

1. The herein described ball slinger com-

prising a handle provided at its outer end with a longitudinal slot of liberal width 25 producing two fork arms, each weakened on its outer side and dished on its inner side at its extremity to produce a pocket for holding the ball, and an adjustable device for drawing the fork arms toward each 30 other at a point below where they are weakened.

2. The herein described missile slinger comprising a handle having normally spaced resilient arms at its outer end, each 35 dished on its inner face at its extremity and complementing the opposite dished face to produce a pocket, and a screw through said arms for adjusting them toward each other.

In testimony whereof I have hereunto set 40 my hand in presence of two subscribing witnesses.

FREDERICK B. KIRKNESS.
